(57) CLAIM

The ornamental design for a golf club head, as shown and described.

DESCRIPTION

FIG. 1 is a top elevational view thereof;

FIG. 2 is a front view thereof;

FIG. 3 is a rear view thereof;

FIG. 4 is a bottom elevational view thereof;

FIG. 5 is toe side thereof;

FIG. 6 is a heel side thereof; and

FIG. 7 is a cross-sectional view of the golf club head along line 7-7 of FIG. 2.

The broken line showing is for illustrative purposes only and forms no part of the claimed design.
